UNITED STATES PATENT OFFICE.

ROBERT G. MACKAY, OF CHICAGO, ILLINOIS.

DESIGN FOR A FIREPLACE.

Application filed May 8, 1925. Serial No. 13,364. Term of patent 3½ years.

To all whom it may concern:

Be it known that I, ROBERT G. MACKAY, a citizen of the United States, residing at Chicago, in the county of Cook and State of Illinois, have invented a new, original, and ornamental Design for a Fireplace Manufactured and Sold as a Unit, of which the following is a specification, reference being had to the accompanying drawing, in which a perspective of the design is shown.

I claim:—

The ornamental design for a fireplace, as shown.

In testimony whereof I affix my signature.

ROBERT G. MACKAY.
